MODULATING SYSTEM

Howard M. Crosby, Schenectady, N. Y., assignor
to General Electric Company, a corporation of
New York

Application November 2, 1942, Serial No. 464,163

5 Claims. (Cl. 179—171.5)

This invention relates to modulating systems and more particularly to modulating circuits for radio telephone transmitters.

In certain cases of radio telephonic transmission it may be desirable to vary the radio frequency power output of the transmitter. For example, a radio broadcasting station may operate on a given power output during the daylight hours and on a reduced power output during the evening.

In a conventional anode-modulated amplifier circuit the radio frequency output of the oscillator or radio frequency amplifier electron discharge device varies with the second power of any voltage applied to its anode circuit and the anode circuit impedance of the discharge device is constant. By inserting a resistance in series with the anode circuit, a reduction in D. C. anode voltage is obtained which reduces the radio frequency output according to the amount of voltage drop through the resistance. At the same time the applied audio or modulating voltage is reduced in the same proportion so that the original percentage of modulation of the radio frequency output is effectively maintained. However, the modulator is now working into a higher load impedance than before and if the variation in output is substantial the power transfer is inefficient, since maximum power is transferred from a generator to a load when their impedances are equal to each other. Furthermore, serious distortion is often produced in many types of modulators when the load impedance changes appreciably.

Therefore, it is an object of my invention to provide a new and improved anode modulation system in which the radio frequency power output may be varied but the load impedance presented to the modulation or signal potential is maintained substantially constant.

The novel features which I believe to be characteristic of my invention are set forth in the appended claims. My invention itself, however, both as to its organization and method of operation may best be understood by reference to the following description taken in connection with the accompanying drawing which represents schematically a circuit embodying the principles of my invention.

Referring to the drawing there is illustrated a source of radio frequency excitation 10 including an electron discharge device 11 including a cathode 12, a control electrode 13, and an anode 14. The output of the electron discharge device 11 is fed to a suitable radio frequency output circuit 15 which may be an additional amplifier or an antenna coupling circuit, for example. Thus, the

radio frequency electromotive force applied to the control electrode is reproduced on the anode.

There is illustrated in the drawing an anode or plate modulation system for modulating the radio frequency current being conducted to the output stage 15. The anode circuit for the discharge device 11 includes a suitable radio frequency impedance indicated by the numeral 16. A source of positive operating potential is indicated by the numeral 17 and a suitable source of modulating or signal potential is indicated by the numeral 18. The modulating potential may be introduced into the anode circuit by a modulation transformer 19 fed from any suitable modulation system but it will be understood that any suitable means of applying a modulating potential in series with the anode and source of anode potential may be employed.

In order to vary the radio frequency output from the device 11 one or more resistors 20 and 21 may be inserted in the anode circuit and there is provided means for varying the amount of resistance in the circuit. For this purpose I have provided a power control switch 22 having a plurality of contacts. The contact 23 is connected to the anode circuit between the element 16 and the resistor 21. The contact 24 is connected to a point between the resistances 20 and 21 while contact 25 remains open. The movable portion 26 of the switch 22 is connected to a point between the resistance 20 and the source of modulating potential 18. When the switch arm 26 engages the contact 23, the resistances 20 and 21 are shunted and no resistance is introduced into the anode circuit whereas if the switch is on contact 24 the resistance 21 is included in the anode circuit, and if the switch arm is moved to the contact 25 both resistances are included. The sizes of the resistors 20 and 21 are chosen according to the percentage change in output desired. For example, if the power output with the switch engaging contact 23 is considered to be 100% output, and if the resistance 21 is chosen of such size that the anode current of the discharge device 11 produces a voltage drop there-through equal to $(1-1/\sqrt{2})$ times the anode supply, then with the switch in engagement with contact 24 and the resistance 21 in the anode circuit, the output is cut down to 50%; and if both resistances 20 and 21 are included in the circuit and the value of resistance 20 is such that when added to the value of resistance 21 a voltage drop is produced equal to one-half the anode supply, the output is cut down to 25% of the original amount.

As previously explained, with one or both resistances 20, 21 in the circuit the modulator is working into a higher load impedance than before, and assuming that the circuit had originally been properly designed so that the impedance of the source of modulation potential 18 and the anode circuit of the discharge device 11 were substantially equal, the modulator is no longer working at its best efficiency or minimum distortion. In order to avoid this undesirable condition there are provided resistors 27 and 28 which may be inserted as shunt loads on the source of modulating potential 18 in such a manner as to keep the total modulator load impedance constant under all adjustments of the power control switch 22. For this purpose the switch 22 is provided with contacts 29, 30 and 31 so disposed that the arm 26 of the switch engages contacts 23 and 29, contacts 24 and 30, and contacts 25 and 31, respectively, at the same time. The contact 29 is open, the contact 30 is connected to one end of the resistance 27 and the contact 31 is connected to the other end of the resistance 27. The resistance 28 is connected between the low potential end of the modulating source 18 and the aforementioned other end of the resistance 27. Therefore, when the switch 22 is in the first position, i. e., when it engages the contacts 23 and 29, there is no resistance introduced into the anode circuit and there is no shunting resistance connected around the source 18. In the position of the switch in which the arm 26 engages the contacts 24 and 30 the resistance 21 is connected in the anode circuit and the series-connected resistances 27 and 28 are connected in shunt across the secondary of the transformer 19. In the third position of the switch, that is, when the contacts 25 and 31 are engaged by the switch 26, both resistances 20 and 21 are connected in the anode circuit but only the resistance 28 is in shunt to the secondary of the transformer 19. It will thus be seen that by properly choosing the value of the resistances, as the series resistance increases the shunt resistance decreases whereby the total modulator load impedance is maintained substantially constant under any adjustment of the power control switch.

While I have shown and described a single embodiment of my invention it will, of course, be understood that I do not wish to be limited thereto, since modifications may be made in the circuit arrangement and in the instrumentalities employed without departing from the spirit and scope of my invention as set forth in the appended claims.

What I claim as new and desire to secure by Letters Patent of the United States is:

1. In combination, an electron discharge device having an anode, a cathode, and a control electrode, means for applying a radio frequency electromotive force to said control electrode for reproduction on said anode, a circuit between said anode and said cathode including a source of operating potential and a source of signal po-

tential, means for varying the impedance of said anode circuit to vary the radio frequency output of said device, and means for varying the impedance of said anode circuit to maintain constant the total load impedance presented to said source of signal potential.

2. In combination, an electron discharge device having an anode, a cathode, and a control electrode, means for applying a radio frequency electromotive force to said control electrode for reproduction on said anode, a circuit between said anode and said cathode including a source of operating potential and a source of signal potential, and means for varying the radio frequency output of said device, said means comprising means for varying the impedance of said circuit to currents from both of said sources while maintaining the load on said signal source constant.

3. In combination, an electron discharge device having an anode, a cathode, and a control electrode, means for applying a radio frequency electromotive force to said control electrode for reproduction on said anode, a circuit between said anode and said cathode including a source of operating potential and a source of signal potential, and means for varying the voltage applied to said anode in order to vary the radio frequency output of said tube, said last means operating undesirably to change the load on said signal source, and means for compensating for said changes in the load on said signal source, thereby to maintain constant said load.

4. In combination, an electron discharge device having an anode, a cathode, and a control electrode, means for applying a radio frequency electromotive force to said control electrode for reproduction on said anode, a circuit between said anode and said cathode including a source of operating potential and a source of signal potential, means for varying the amount of said resistance to vary the radio frequency output power of said device, and means for adjusting the load on said source of signal potential in a manner to present a constant total load impedance to said source of signal potential as said resistance is varied.

5. In combination, an electron discharge device having an anode, a cathode, and a control electrode, means for applying a radio frequency electromotive force to said control electrode for reproduction on said anode, a circuit between said anode and said cathode including a source of operating potential and a source of signal potential, a plurality of resistors arranged to be connected in series in said anode circuit, a plurality of resistors arranged to be connected in shunt with said source of signal potential, and means for selectively and simultaneously changing the connections of both said series and said shunt resistors to vary the radio frequency output of said device while maintaining substantially constant the load on said source of signal potential.

HOWARD M. CROSBY.
